FLUID ACTUATED SNAP-ACTING
GATE VALVE

James E. Elkington, San Francisco, Calif.

Application December 27, 1948, Serial No. 67,287

6 Claims. (Cl. 137—701)

1

This invention relates to a dish washing machine and particularly to a hydraulic actuator or prime mover for reciprocating a dish tray moving rack in and through the washing zone of said machine; said actuator being made to reciprocate by hydraulic pressure in alternating cycles.

An object of the invention is to provide an hydraulic actuator which includes a plunger made to reciprocate by applying hydraulic pressure in alternating cycles to opposite faces of the plunger through the instrumentality of a valve timer synchronized to operate with the plunger and to control its operation.

In the accompanying drawings:

Fig. 1 is a side elevation, partly broken away, of a dish washing machine constructed in accordance with my invention, showing my hydraulic reciprocator operatively applied thereto.

Fig. 2 is a longitudinal section of an hydraulic actuator or prime mover constructed in accordance with my invention, illustrated in its application to a slide rack on a dish washing machine, the plunger of the actuator being secured to the rack while the actuator mechanism is fixed on one end of the washing machine structure.

Fig. 3 is an enlarged cross-section taken through the valve chamber on the line 3—3 of Fig. 2.

Fig. 4 is an exploded view of the valve and its guide members.

Fig. 5 is a fragmentary view on an enlarged scale of a part of the valve actuating mechanism.

Fig. 6 is a view in front elevation of the valve chamber without the valve.

In detail the construction illustrated in the drawings comprises a dish washing machine which in its entirety is designated by the numeral 10. This dish washing machine includes, in addition to the necessary structural framework, a water tank 11, fluid spray pipes 12, a fluid pump 13 and a motor 14, a reciprocating rack 15 mounted over the tank 11 and between the spray pipes 12 for moving trays 18 of dishes and the like through the washing zone on the parallel guides 19 which extend longitudinally through the machine.

The dirty dishes or other articles to be washed are placed by hand in trays 18 and the loaded trays are placed on the entrant end of guides 19. The guides 19 are formed of spaced complementary angle bars and beneath said guides the reciprocating rack 15 is slidably mounted. The rack 15 is of known construction, and it is provided, at spaced intervals between the ends thereof, with counterweighted pawls 25 pivotally

2

mounted thereon. The upper end 26 of each pawl 25 is adapted to engage ribs or serrations (not shown) on the under side of the dish trays 18 for the purpose of intermittently advancing said dish trays through the washing process from the entrant end of the tray guides 19 to the discharge end thereof. The rack 15 is reciprocated in a horizontal plane in the manner to be hereinafter described. When the rack is reciprocated forwardly toward the discharge end of the washing machine, the upper end 26 of each pawl engages the dish trays 18 and advances them, with an intermittent movement, along the tray guides 19. On the return stroke of the rack 15 the pivoted pawls 25 disengage from the dish trays but automatically swing upwardly into contact with the dish trays upon the start of the forward stroke of the rack 15.

The type of rack 15 hereinabove described for advancing the dish trays through the wash zone is only one of many types of similar racks which might be utilized to be actuated by my reciprocating mechanism. For example, a rack swingably supported, pendulum style, might also be actuated by my hydraulic actuator or a pair of parallel endless belts could be actuated intermittently by my prime mover for moving the dish trays through the machine. It is to be understood that while I have developed the prime mover particularly for its use on a dish washing machine, that the reciprocative impulses developed by it could be applied to or utilized on many other machines of a type and kind needing a reciprocative movement in some phase of their operations.

A cylinder 30 is mounted on a base 31 and is closed at the end opposite the base 31 by a cap 32a. The cap 32a is secured to the base 31 by rods, welding or otherwise.

The cap 32a is drilled centrally with the axis of the cylinder 30 to provide a bore in which a hollow shaft or inner cylinder 32 is slidably confined. The outer end of the shaft 32 is fixed to the cross member 33 of the rack, while the inner end of the shaft 32, within the cylinder 30, has a plunger or piston 34 mounted thereon.

The shaft 32 is drilled axially at 35 and it is closed at one end by a solid plug 36 and at its other end it is provided with a hollow plug 37 which slidably receives an actuator rod 38. At one end the actuator rod is provided with an enlarged head 39 and at its other end it extends through the base 31 into a valve chamber 45.

The valve structure comprises a valve plate or 55 slide valve 46 slidably confined between a pair of

3

opposing guides 47 and 48, the upper guide 47 being sweated into the valve chamber and the lower guide 48 being secured by means of a machine screw 49. As will be seen, the guide members 47 and 48 are beveled, and the valve 46 is provided with complementary beveled edges. Also, the lower guide member 48 is drilled at 50 to receive coil springs 51 which resiliently urge steel balls 52 against the slide valve 46.

The slide valve 46 is a generally flat plate like member which is drilled through as illustrated to provide an ovate slot 53 and spaced oil holes 54 and 55 and an ovate socket 56 disposed between and aligned with the oil holes.

The outer end of the actuator rod 38 extends through a pin or cross member 57 to which it is secured by a set screw 58. The pin 57 is free to slide in slot 53, and bearing against it are two sleeves 59, each of which is recessed at 60 to provide a bearing surface for the pin 57 and at 61 at right angles to the recess 60 for a purpose explained hereinafter. A rivet 62 is received within each sleeve 59 with its head seated in a recess 63 formed in the chamber 45 and is urged outwardly by a coil spring 64. A washer 65a is slidably and rotatably mounted on the pin 57 as illustrated to balance the forces acting on the pin at the end of its travel.

The valve chamber 45 is provided with three oil holes 65, 66 and 67. The inner hole 65 communicates through a duct 70 with the inner end of the cylinder 30, and the outer hole 67 communicates through a duct 71 with the annular space 72 between the cylinder 30 and an outer cylinder or casing 73 and which communicates with the outer end of cylinder 30 through a port 74. The socket 56 and oil holes 54 and 55 formed in the valve 46 are such that, when the valve is in its extreme outer position as illustrated in Fig. 2, the inner oil hole 65 is aligned with the hole 54, and hence the interior of chamber 45 is in communication with the outer end of cylinder 30. Also, the oil holes 66 and 67 are in communication with each other through the socket 56. Obviously, when the valve 46 is in its extreme inner position, the oil holes 65 and 66 will communicate with each other and the oil hole 67 will be aligned with the hole 55 in the valve; hence, the annular space 72 will communicate with the valve chamber 45.

A pump 80 driven by the motor 14 is provided, and it pumps oil from a sump 81 through a line 82 and a line 83 to the valve chamber 45. Oil is returned through oil hole 66 and a line 84 to the sump 81. In operation the apparatus performs as follows: Oil is pumped to the chamber 45 as described, thus maintaining a fluid pressure therein at all times. Assuming the valve 46 to be in the position shown in Fig. 2, oil flows through hole 54 formed in valve 46, oil hole 65 formed in a valve chamber 45 and duct 70 into the outboard end of cylinder 30, causing piston 34 to move inwardly. Actuator rod 38 remains stationary, as does valve 46, until plug 37 strikes head 39, causing inward movement of pin 57. As pin 57 moves inwardly, springs 64 are compressed and when pin 57 moves past dead center, these springs expand causing pin 57 to snap inwardly very rapidly, carrying valve 46 with it to its opposite or inward position. Meanwhile, oil passes from cylinder 30 through port 74 into the annular space 72, through duct 71, oil hole 67, socket 56, oil hole 68 and line 84 back to the sump 81.

When the valve 46 reaches its inner position, oil will flow from chamber 45 through hole 55 formed in valve 46, oil hole 67, and duct 71 into annular space 72, through port 74 and into the

4

inward end of cylinder 30, thus causing outward movement of piston 34. When plug 37 contacts head 39, it will move actuator rod 38 outwardly, thus causing corresponding movement of pin 57 and valve 46 to restore the latter to its original position, thus completing a cycle of operation.

It will thus be apparent that a reciprocating cylinder has been provided which is specially well adapted to impart intermittent movement to a tray in a dish washing machine, but which also has a wider utility. Among the important advantages of the apparatus may be mentioned the following: The valving action is very rapid, and it will be noted that the arrangement of parts is such that the piston 34 has a relatively long travel corresponding to the requirements of a dish washing machine while the actuator rod 38 and pin 57 have a relatively short travel and the valve 46 an even shorter travel. This results in compactness of the unit and inactivation of the valving mechanism except for a brief interval during each stroke, thus reducing wear of parts. The slide valve 46 is such that wear does not, within reasonable limits, impair its efficiency. Thus, springs 51 and balls 52 keep it in perfect alignment, and they serve the further purpose of providing enough frictional resistance to prevent the valve 46 from moving with the pin 57 until the same has passed dead center. This is important because in past designs difficulty has been encountered, especially after some usage and wear, because the valve would sometimes move slowly with the pin and would stop on dead center with the hydraulic pressure equal on both sides of the piston.

It will also be noted that the sleeves 59 are hollowed out at 60 to bear against and turn on the pin 57, and that they are also hollowed out at 61 at right angles to the hollows 60, so as to accommodate the actuator rod 38 in either of its extreme positions. Thus, as illustrated, when the rod 38 is in its outermost position, the hollows or grooves 61 are cupped over the rod 38, thus allowing greater compactness of construction.

Also, as mentioned hereinabove, the washer 65a balances the forces acting on pin 57 at the end of its travel. Thus, when the pin 57 strikes one end of slot 53, in the absence of the washer 65a, a torque would result tending to break or bend the pin. This is obviated by the washer 65a.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. A valve structure of the character described, comprising a valve chamber having an inlet port and spaced outlet ports, a valve member slidable within said chamber to open either of said outlet ports and to close the other outlet port, said valve member being formed with a slot, and means for actuating said valve member comprising a reciprocable rod having a pin at one end received in said slot, and resilient radial members each bearing against said pin at one end and at the opposite end against said valve chamber and operable to compress as said pin approaches dead center and to expand when said pin passes dead center so as to quickly slide said valve member to its opposite position.

2. A valve structure of the character described, comprising a valve chamber having an inlet port and spaced outlet ports, a valve member slidable

within said chamber to open either of said outlet ports and close the other outlet port, said valve member being formed with an elongated slot, and means for actuating said valve member comprising a reciprocable rod having a pin at one end slidable in said slot, a pair of radially disposed sleeves each bearing at its inner end against said pin and resilient means received within the outer end of each said sleeve and bearing against the said valve chamber so as to compress as said pin approaches dead center and thereby quickly slide said valve member to its opposite position.

3. A valve structure of the character described, comprising a valve chamber having an inlet port and spaced outlet ports, a valve member having an elongated slot formed therein, means within said chamber confining said valve member to sliding movement between a first position opening one of said outlet ports and closing the other and an opposite position closing said first mentioned port and opening the other port, said confining means including resilient means bearing against a surface of said valve member to frictionally engage the same and resist movement thereof, and means for actuating said valve member comprising a reciprocable rod having a pin secured thereto at one end and slidable in said slot, and resilient members disposed radially of and bearing against said pin and also bearing against said valve chamber, said resilient members being operable to compress as said pin approaches dead center and to expand when said pin passes dead center so as to quickly slide said valve member to its opposite position.

4. A valve structure comprising a valve chamber, a valve slidable therein and having a longitudinal slot formed therein, a reciprocable member, a pin supported by said member and slidably received at one end in said slot, and abutment means mounted on said pin externally of said slot operable to balance the forces acting on said pin on reaching either end of said slot.

5. A valve structure comprising a valve chamber, a valve slidable therein and having a longitudinal slot formed therein, a reciprocable member, a pin supported by said member and slidably received at one end in said slot, and a disc-like member rotatably mounted on the other end of said pin operable to abut said chamber when said pin reaches either end of said slot.

10 6. In a valve a casing, a slidable valve plate within said casing, a valve plate operating rod extending into said casing, a lost-motion pin and slot connection between said plate, rod and resilient means operable when the pin has been moved in either direction past the center of the slot to continue its movement to the end of the slot and thereafter to move the rod and plate together, said spring means comprising a spring toggle mounted within said casing, and comprising a pair of pivotally movable spring-urged telescopic members each engaging the pin at one end and the adjacent side of the casing at the other.

JAMES E. ELKINGTON.
